UNITED STATES PATENT OFFICE

93,564

DESIGN FOR AN ADVERTISING DISPLAY CARD

Harry Lewy, Baltimore, Md.

Application July 27, 1934, Serial No. 52,724

Term of patent 7 years

To all whom it may concern:

Be it known that I, HARRY LEWY, a citizen of the United States of America, residing at Baltimore, in the State of Maryland, have invented a new, original, and ornamental Design for an Advertising Display Card, of which the following is a specification, reference being had to the accompanying drawing, forming a part thereof.

What I claim is:—

The ornamental design for an advertising display card substantially as shown.

HARRY LEWY.
